UNITED STATES PATENT OFFICE.

KARL KIEFER, OF CINCINNATI, OHIO.

FILLING APPARATUS.

1,227,628.

Specification of Letters Patent. Patented May 29, 1917.

Application filed August 31, 1915. Serial No. 48,373.

To all whom it may concern:

Be it known that I, KARL KIEFER, a citizen of the United States, residing at Cincinnati, in the county of Hamilton and State of Ohio, have invented certain new and useful Improvements in Filling Apparatus, of which the following is a specification.

My invention relates to filling machines; 10 and its object is to fill a plurality of containers, especially bottles of smaller sizes, such as panel bottles, accurately to a uniform height.

My invention consists in the parts and in 15 the details of construction and arrangement of parts as will herein be more fully described and claimed.

In the drawings:

Figure 1 is a plan view of a filling head 20 embodying my invention, the vertical guide bar being in cross-section;

Fig. 2 is a partial vertical cross section on the line $x-x$ of Fig. 1; and

Fig. 3 is a vertical cross section on the 25 line $y-y$ of Fig. 1, showing the parts in a different position.

The filling head shown is designed to be mounted and guided in a suitable machine frame by means of a vertical rectangular bar 1 rigidly connected to the upper side of a horizontal bar 2 that forms the main supporting element of the filling head. A stud 3 projecting horizontally from the connection of the bars 1 and 2 serves for connection with suitable operating mechanism, not here shown, to move the filling head up and down. At the ends, the horizontal bar 2 has downwardly extending rods 4 from which horizontal arms 5 project back and carry the manifold 6 which is closed at one end by a plug 7 and at the other end has suitable means for connecting to the source of supply of the liquid with which the containers are to be filled, such as the elbow 8. Some distance below the bar 2 is another horizontal bar 9 with its end parts fixed to the rods 4, and supported and guided on the lower end parts of the rods 4 is a bottle-top guide 10 yieldably held down by 40 springs 11 coiled around the rods 4 under the lower bar 9.

As here shown, there are six filling tubes 12 each mounted in a connection head 13 having a shank 14 extending up through 45 the lower bar 9 and into the main upper bar 2, so that the connection head may slide

up and down and be guided by these bars. Embracing each shank 14 between the upper and lower bars 2 and 9 is a clamping member 15 held to move up and down with 60 the shank by means of a pin 15' extending through the member and the shank. Compressed between the member 15 and the upper bar 2 around each shank 14, is a coiled spring 16 which thus yieldably holds the 65 connection head with its shank and clamping member down toward the lower bar 9.

Each connection head 13 has a lower bore or passage 17 and an upper bore or passage 18. The filling tube 12 terminates in and 70 communicates with the lower passage 17, but inside the filling tube is a vent or overflow tube 19 which passes up through the lower passage 17 and communicates with the upper passage 18. The lower end 20 75 of this tube 19 opens laterally through the filling tube 12 slightly above the lower end of the tube 12.

Communicating with the bores or passages 17 and 18 and leading forwardly therefrom are tubes 21 and 22, respectively, which curve upward and backward, terminating at about the level of the lower side of the clamping member 15.

The manifold 6 above referred to, has, 85 inside, a partition 23 with its ends 24 curving back and joining the inner sides of the manifold 6, thereby forming distinct inlet and overflow compartments 25 and 26, respectively, in the manifold. A nipple 27 90 near one end of the compartment 26 forms an outlet therefor. The manifold 6 has, for each filling tube, a forwardly extending nipple 28 communicating with the inlet compartment 25, and also for each vent or overflow tube a forwardly extending nipple 29 95 that extends back through the inlet compartment 25 and communicates through the partition 23 with the overflow compartment 26. Connected to these nipples 28 and 29 100 are flexible tubes 30 and 31 which extend through the space between the clamping member 15 and the lower bar 9.

Thus each filling tube 12 is connected 105 through the passage 17, curved tube 21, flexible tube 30 and nipple 28 with the inlet compartment 25 of the manifold; and each overflow or vent tube 19 is connected through the passage 18, curved tube 22, 110 flexible tube 31 and nipple 29 with the overflow compartment 26 of the manifold,

and the flexibility of the tubes 30 and 31 permits this connection to be made while allowing the connection head 13 with the parts that it carries to move up and down with respect to the manifold 6 which is rigidly connected to the bars 2 and 9 and rods 4 by the arms 5, as before described.

Furthermore, since these flexible tubes 30 and 31 extend between the bar 9 and the clamping member 15 they will, when the connecting head 13 is pressed down by the spring 16 acting against the clamping member 15 on the shank of the connection head, be clamped by said clamping member 15 down against the upper side of the bar 9 and will thus be flattened and entirely closed against the passage of liquid, as shown in Fig. 2. Each clamping member 15 preferably has on its lower side, a rib 15' which has its lower side rounded to effectively bear on the tubes 30 and 31 without injuring them.

Mounted on each filling tube 12 is a stop member 32 with a gasket 33 below it and held positively against upward movement on the tube by a spacing pin 34 fitting in sockets in the stop member and in the lower side of the connection head 13.

When the filling head is brought down the bottle-top guide 10 will pass over the top of the bottle and the filling tube 12 will be inserted into the bottle until the top of the bottle is engaged by the gasket 33 which will effectively close the bottle against communication with the outer atmosphere. Further depression of the filling head then results in a movement of the connection head 13 upward relative to the frame of the filling head against the pressure of the spring 16, thus raising the clamping member 15 from the position shown in Fig. 2 to that shown in Fig. 3, and thus opening the tubes 30 and 31, allowing liquid to flow through the inlet passages and filling tube 12 into the bottle; the air that was in the bottle being forced out through the vent or overflow tube 19 and the overflow passages. The liquid will continue to flow into the bottle until its level reaches the lower open end 20 of the vent or overflow tube 19. Then instead of rising higher in the bottle it will flow out through the overflow or vent tube 19 and the overflow passages as long as liquid continues to be supplied through the filling tube. Of course the attendant raises the filling head as soon as possible after the desired level has been reached as above described, but any delay in raising will not result in filling or overflow of the bottle, but merely in a flow out through the overflow passages. Upon raising the filling head and disengagement of the gasket 33 from the bottle top, the connection head 13 and clamping member 15 will be moved down by the spring 16, closing the tubes 30 and 31

again, as shown in Fig. 2, and stop further flow of the liquid.

So that the clamping members 15 will not bear upon and permanently distort the flexible tubes 30 and 31 when the machine is not in use, the connection heads 13 are held up by means of hooks 35 straddling the connection heads and engaging over the upper edge of the bar 9. Preferably these hooks are so formed that at the first depression of the filling head they will fall forward away from the bar 9 and will require manual engagement therewith when use of the machine is to be again discontinued.

By withdrawing the pin 15' from the clamping member 15 and shank 14, the connection head 13 with its tubes may be removed downwardly from the filling head and the flexible tubes 30 and 31 may be pulled from over the ends of the tubes 21 and 22, so that another connection head with a similar shank 14 and tubes 21 and 22 but with a filling tube of different size, may be substituted in the machine for filling bottles of a different size.

It will be understood that the inlet and overflow connections to the manifold 6 and the overflow nipple 27 will be flexible, since the entire filling head must move up and down with respect to the source of liquid supply and to the container that receives the overflowing liquid.

By utilizing the flexible tubes 30 and 31 as the means for controlling the outflow of liquid simply by clamping them as before described, a practical and efficient filling apparatus is provided without complication, such as is generally involved in providing valves for the filling tubes. The flexible connections for each filling tube and vent or overflow tube are provided with an individual clamping means 15 operated independently of the clamping means of the other tubes rather than by having a single clamping means acting upon all of the flexible tubes, because it is found that the apparatus works more smoothly upon the various bottles which slightly vary in size and would thus cause some irregularity of operation and binding if all of the clamping means were rigidly connected, such as by being made of a single bar. However, it will be understood that this and other minor details of my invention above described, are subject to modification in accordance with varying requirements.

Having fully described my invention, what I claim as new and desire to secure by Letters Patent is:

1. In filling apparatus, in combination with supporting element that is movable up and down, a filling tube and liquid supply means mounted upon and movable up and down with said element, a flexible connection between said tube and said means, 130

and clamping means acting on said flexible connection to close it.

2. In filling apparatus, in combination with a supporting element that is movable up and down, a filling tube and a vent or overflow tube and means having an inlet passage and an overflow passage mounted upon and movable up and down with said element, flexible tubes connecting the filling tube and the vent or overflow tube with said inlet passage and said overflow passage, respectively, and clamping means acting upon said flexible tubes to close them.

3. In filling apparatus, in combination with supporting element that is movable up and down, a filling tube and liquid supply means mounted upon and movable up and down with said element, a flexible connection between said tube and said means, clamping means acting on said flexible connection to close it, and a detachable connection between said filling tube and said clamping means.

4. In filling apparatus, in combination with supporting element that is movable up and down, a filling tube and liquid supply means, mounted upon and movable up and down with said element, a flexible connection between said tube and said means, clamping means acting on said flexible connection to close it, and means acting to remove the action of said clamping means from said flexible connection when said filling tube is connected with a container to be filled therefrom.

5. In filling apparatus, in combination with a supporting element that is movable up and down, a filling tube and a vent or overflow tube and means having an inlet passage and an overflow passage mounted upon and movable up and down with said element, flexible tubes connecting the filling tube and the vent or overflow tube with said inlet passage and said overflow passage, respectively, clamping means acting upon said flexible tubes to close them, and means acting to remove the action of said clamping means from said flexible tubes when said filling tube and said vent or overflow tube are connected with a container to be filled from said filling tube.

6. In filling apparatus, in combination with a filling tube and liquid supply means, a flexible connection between said tube and said means, clamping means acting on said flexible connection to close it, means acting to remove the action of said clamping means from said flexible connection when said filling tube is connected with a container to be filled therefrom, and means holding said clamping means and preventing its action on said flexible connection when the apparatus is not in use.

7. In filling apparatus, in combination with a filling tube and a vent or overflow

tube opening near the lower end of the filling tube, and inlet and overflow means for said apparatus, a connection head having distinct passages in it, with respective ones of which said filling tube and said vent or overflow tube communicate, a shank extending up from said connection head, upper and lower guiding means for said shank, a clamping member fixed on said shank above the lower guiding means, flexible tubes connecting with the respective passages in said connection head and extending between said clamping member and said lower guiding means, and connecting, respectively, with said inlet and said overflow means, engaging means on said filling tube to engage with the top of the container when the filling tube is inserted therein and raise said tube and connection head, and means yieldably holding said connection head down, whereby the clamping means clamps said flexible tubes between it and said lower guiding means until raised with said connection head.

8. In filling apparatus, in combination with a filling tube and a vent or overflow tube opening near the lower end of the filling tube, and inlet and overflow means for said apparatus, a connection head having distinct passages in it, with respective ones of which said filling tube and said vent or overflow tube communicate, a shank extending up from said connection head, upper and lower guiding means for said shank, a clamping member fixed on said shank above the lower guiding means, flexible tubes connecting with the respective passages in said connection head and extending between said clamping member and said lower guiding means, and connecting, respectively, with said inlet and said overflow means, engaging means on said filling tube to engage with the top of the container when the filling tube is inserted therein and raise said tube and connection head, and a spring between said clamping means and said upper guiding means yieldably holding the connection head and clamping means down, whereby said clamping means clamps said flexible tubes between it and said lower guiding means until raised with said connection head.

9. In filling apparatus, in combination with a filling tube and a vent or overflow tube opening near the lower end of the filling tube, and inlet and overflow means for said apparatus, a connection head having distinct passages in it, with respective ones of which said filling tube and said vent or overflow tube communicate, a shank extending up from said connection head, upper and lower guiding means for said shank, a clamping member fixed on said shank above the lower guiding means, flexible tubes connecting with the respective passages in said

- connection head and extending between said clamping member and said lower guiding means, and connecting, respectively, with said inlet and said overflow means, en-
 5 gaging means on said filling tube to engage with the top of the container when the filling tube is inserted therein and raise said tube and connection head, means yieldably holding said connection head down, where-
 10 by the clamping means clamps said flexible tubes between it and said lower guiding means until raised with said connection head, and a detachable connection between said shank and said clamping member, per-
 15 mitting said connection to be withdrawn from said clamping member and said guiding means.
10. In filling apparatus, in combination with a filling tube and a vent or overflow tube opening near the lower end of the filling tube, and inlet and overflow means for said apparatus, a connection head having distinct passages in it, with respective ones of which said filling tube and said vent or overflow tube communicate, a shank extending up from said connection head, upper and lower guiding means for said shank, a clamping member fixed on said shank above the lower guiding means, flexible tubes connecting with the respective passages in said connection head and extending between said clamping member and said lower guiding means, and connecting, respectively, with said inlet and said overflow means, engag-
 35 ing means on said filling tube to engage with the top of the container when the filling tube is inserted therein and raise said tube and connection head, means yieldably holding said connection head down, where-
 40 by the clamping means clamps said flexible tubes between it and said lower guiding means until raised with said connection head, and a hook on said connection head engaging with said lower guiding means
 45 to hold the connection head up, and thereby hold the clamping means up from said tubes when the apparatus is not in use.
11. In filling apparatus, in combination with a filling tube and a vent or overflow tube therein opening near the lower end thereof, and inlet and overflow means for said apparatus, a connection head having a lower passage with which said filling tube communicates, and an upper passage with which said vent or overflow tube communicates, flexible connections between the respective passages in the connection head and said inlet and overflow means, and clamping means to close said flexible connections against the passage of liquid.
12. In filling apparatus, a series of filling tubes and a vent or overflow tube for each filling tube, a manifold comprising an inlet compartment and an overflow compartment, means rigidly supporting said mani-
 65 fold and guiding said filling tubes and vent or overflow tubes for up and down movement with respect to the supporting means and manifold, a flexible connection from each filling tube to the inlet compartment, a flexible connection from each vent or overflow tube to the overflow compartment, and clamping means to close said flexible connections against the passage of liquid.
13. In filling apparatus, a series of filling tubes and a vent or overflow tube for each filling tube, a manifold comprising an inlet compartment and an overflow compartment, means rigidly supporting said manifold and guiding said filling tubes and vent or overflow tubes for up and down movement with respect to the supporting means and manifold, a flexible connection from each filling tube to the inlet compartment, a flexible connection from each vent or overflow tube to the overflow compartment, and a clamping means for the flexible connections of each filling tube and its vent or overflow tube operative independently of the clamping means of the other flexible connections.
14. In filling apparatus, a series of filling tubes and a vent or overflow tube for each filling tube, a manifold comprising an inlet compartment and an overflow compartment, means rigidly supporting said manifold and supporting and guiding said filling tubes and vent or overflow tubes for up and down movement with respect to the supporting means and manifold, a flexible connection from each filling tube to the inlet compartment, a flexible connection from each vent or overflow tube to the overflow compartment, clamping means to close said flexible connections against the passage of liquid, said manifold comprising an outer tube with a longitudinal partition inside the tube with ends closed against the inner sides of the tube, forming an inlet compartment and an overflow compartment, an inlet connection to the inlet compartment and an outlet connection to the overflow compartment, a nipple to receive the flexible connection from each filling tube and ex-
 100 tends only through the outer wall of said manifold, and a nipple to receive the flexible connection of each vent or overflow tube and extending through the outer wall, across the inlet compartment, and through the partition, to the overflow compartment.
15. In filling apparatus, in combination with a series of filling tubes, and a vent or overflow tube for each filling tube, a manifold comprising an outer tube and a longitudinal partition inside the tube with ends closed against the inner sides of the tube forming an inlet compartment and an overflow compartment, an inlet connection to the inlet compartment and an outlet connection to the overflow compartment, a nipple

for connection to each filling tube, extending only through the outer wall of the manifold tube into the inlet compartment, a nipple for connection to each vent or overflow tube, extending through the outer wall, across the inlet compartment, and through the partition into the overflow compartment, and a connection from each filling tube and vent or overflow tube to its respective nipple on the manifold.

16. In filling apparatus, in combination with a filling tube, a vent or overflow tube inside the filling tube and opening near the lower end thereof, a connection head having a lower passage and an upper passage with which, respectively, said filling tube and said vent or overflow tube communicate, a shank extending up from said connection head, upper and lower guiding means for said shank, rigid tubes fixed in said connecting head, communicating, re-

spectively, with the lower and upper passages therein and extending outward and curving upward and back toward said shank, means having an inlet passage and 25 an outlet passage on the side of said supporting and guiding means opposite from said curved tubes, flexible tubes connecting said curved tubes, respectively, with said inlet and outlet passages, clamping means on 30 said shank above said lower supporting and guiding means, said flexible tubes extending between this clamping means and this guiding means, and means for yieldably holding said connection head down in its guiding 35 means and clamping said flexible tubes between said clamping means and said lower guiding means, to close said flexible tubes.
